HARROW

Alexus C. Lindgren, Chicago, Ill., assignor to International Harvester Company, a corporation of New Jersey

Application June 8, 1933, Serial No. 674,915

3 Claims. (Cl. 55—104)

The invention relates to harrows of the pivoted tooth bar type and, more specifically, to the frame construction thereof.

The main object of the invention is to simplify and improve the structure of multiple unit spring tooth harrows of the pivoted tooth bar type by eliminating certain of the central longitudinal runner bars ordinarily employed in such harrows, and to provide a flexible and easily controlled harrow without making use of separate harrow frames for each unit as has heretofore been the practice.

The novel construction by which the foregoing and other objects and improved features are attained is described hereinafter and illustrated in the accompanying drawings, where:

Figure 1 is a plan view of a harrow embodying the invention;

Figure 2 is a side elevation;

Figure 3 is a detail view on line 3—3 of Figure 1; and,

Figure 4 is a detail view on line 4—4 of Figure 1.

In the present disclosure there is illustrated a double harrow comprising two harrow units or sections and a unitary draft frame. The draft frame has a transversely extended draft bar 10, forwardly converging bars 11 having the forward ends 12 disposed in parallel, spaced relation, and a central tongue or slide bar 13 extending between

the ends 12 of the bars 11. A bracket comprising vertical plates 14 connects the ends 12 of the converging bars. The draft bar 10 has attached to it three uniformly spaced runner bars trailing loosely therefrom. These consist of two outer

runner bars 15, the forward ends of which are bent upwardly and pivotally connected at 16 to the ends of the draft bar 10, and a single intermediate or central runner bar 17 identical in form to the outer bars and pivotally connected

to the draft bar at 17^a. All three bars are, therefore, connected on the same transverse axis. The runner bars are preferably formed of angle iron sections with one web upright and the other web forming a runner-like surface on which the har-

row is supported when the teeth are raised to transport position. The runner bars are provided with upright bearing brackets 18 fixed to the vertical web of the runner bars and arranged in transverse alignment on the respective bars in spaced relation along the length of these bars, as illustrated. These brackets carry sets of axially aligned tooth carrying bars 19 which are illustrated as arranged in pairs with the ends of the respective bars of each pair pivoted on the

outer runner members 15 and the single central member 17.

To effect an offset pivotal connection between the tooth bars and the brackets on the runner bars, the ends of the runner bars are provided with angular extensions 20 at each end, the vertical arms of which are loosely pivoted on transverse pins 21 on the brackets 18. As each bracket on the central runner member 17 serves to support the adjacent inner ends of a pair of tooth bars, these brackets are provided with longer pins 22 projecting from each side of the bracket for reception of the respective angular extensions 20, as illustrated by Figure 3. The tooth bars carry uniformly spaced harrow teeth 23, which are here illustrated as spring teeth. These are arranged in staggered relation on the respective bars, and, to effect uniformity in the staggering of the teeth, one of the rear tooth bars 19 is extended, as at 24 (Figure 4) to a point beyond the central runner bar 16, so that it overhangs the same, and one of the teeth is secured to this overhanging end, as at 23^a. In order to provide clearance for the extended end 24, the end of the adjacent tooth bar on the other unit is modified by shortening it and by having its angular extension 25 bent downwardly and then upwardly, as shown in Figure 4, to provide a pivot arm in axial alignment with the angular extension 20 on the companion bar.

The frame construction and manner of mounting the tooth bars above described provides a flexible structure in which the two lateral extensions or units composing the harrow may flex about a central longitudinal line, due to the loose pivotal connections of the inner ends of the tooth bars to the pivot pins 22, while the tooth bars may rock about their pivots on the brackets 18. The tooth bars on each unit are connected for simultaneous rocking movement by means of rocker bars 26 connected to upright arms 27 on the respective tooth bars.

Rocking of the tooth bars on both units to lift and lower the teeth is preferably effected simultaneously by means of a draft operated device such as described and claimed in patent to John son et al. 1,923,930, August 22, 1933. This consists of forwardly converging links 28 pivotally connected at their rear ends to the respective rocker bars 26 and pivoted at their front ends to a slidably draft head 29 mounted on the forward portion of the tongue or slide bar 13. This draft head has a clevis 30 secured to its forward end and is provided with ratchet teeth 31 cooperating with a latch lever 32 pivoted on a transverse pin connecting the bracket plates 14 and controlled

100

105

110

by a pull cord 33 from the driver's position on the tractor. The clevis 30 is adapted for connection to a tractor drawbar 34. A pull on the cord releases the draft head 29 and the draft of the 5 tractor will slide the draft head 29 forwardly between the parallel ends 12 of the converging bars 11, thereby rocking the tooth bars and lifting the teeth 23 from the ground. The runner bars 15 and 17 will then rest on the ground and permit 10 easy transportation of the harrow. Reverse movement of the draft head will, of course, lower the teeth.

The construction described is one in which a 15 flexible type of spring tooth harrow is provided without necessitating the use of separate harrow frames as has heretofore been thought necessary, thereby providing a harrow which leaves no un-worked strips of soil between sections and one which is easily manipulated and transported.

20 The preferred embodiment disclosed is subject to modification without departure from the scope of the invention as defined in the following claims.

What is claimed is:

25 1. In a pivot bar harrow, a rigid transverse draft member, outer and inner runner bars trailing loosely from the draft member, upright bearing brackets fixed to the runner bars and arranged in transverse alignment at spaced points 30 along said bars, and sets of axially aligned tooth carrying bars pivoted on said brackets for rocking movement on a transverse axis, two of said aligned tooth bars in each set being pivoted at their adjacent ends on the same bearing bracket.

2. In a pivot bar harrow, a rigid transverse draft member, three equally spaced runner bars pivotally connected respectively to the ends and the center of the draft member to trail therefrom, upright bearing brackets fixed to the runner bars and arranged in transverse alignment at spaced points along said bars, and axially aligned tooth carrying bars connected in pairs to the aligned brackets, the tooth bars of each pair having angular extensions at each end respectively connected pivotally to one bracket on an outer runner bar and to the bracket on the central runner bar for rocking movement on the same transverse axis.

3. In a pivot bar harrow, a rigid transverse draft member, three equally spaced runner bars pivotally connected respectively to the ends and the center of the draft member to trail therefrom, upright bearing brackets fixed to the runner bars and arranged in transverse alignment at spaced points along said bars, axially aligned tooth carrying bars connected in pairs to the aligned brackets, harrow teeth mounted in staggered relation on the respective tooth bars, an angular extension on the end of each tooth bar, said extension on each aligned pair of bars being respectively connected pivotally to one bracket on an outer runner bar and to the bracket on the central runner bar for rocking movement on the same transverse axis, one pair of said tooth bars having one bar thereof overhanging the central runner bar, and a tooth mounted on said overhanging end.

ALEXUS C. LINDGREN.
